UNITED STATES PATENT OFFICE.

HARRY WEARNE, OF RIXHEIM, GERMANY.

DESIGN FOR WALL-PAPER.

SPECIFICATION forming part of Design No. 31,959, dated December 5, 1899.

Application filed November 11, 1899. Serial No. 736,694. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The leading feature of the design consists of a floral chain made up of the representation of nasturtiums, their stems, and leaves.

15 In detail the chain of nasturtiums is placed

between ornamental borders, comprising an inner scroll-scalloped edge, an outer scalloped edge of oak-branches, an intermediate longitudinal bar, and series of transverse bars extending from the inner edge of the longitudinal bar.

Having thus described my invention, I claim as new and desire to secure by Letters Patent—

The design for wall-paper as herein shown and described.

HARRY WEARNE.
